(21) Appl. No.: **29/419,958**

(57) **CLAIM**

(22) Filed: **May 3, 2012**

The ornamental design for a battery pack, as shown and described.

(30) **Foreign Application Priority Data**

Feb. 24, 2012 (KR) 30-2012-0008697

DESCRIPTION

(51) **LOC (9) Cl.** **13-02**

FIG. 1 is a perspective view of a battery pack showing my new design;

(52) **U.S. Cl.**

FIG. 2 is a front view thereof;

USPC **D13/103**

FIG. 3 is a rear view thereof;

(58) **Field of Classification Search**

FIG. 4 is a left side view thereof;

USPC D13/102–106, 110, 118–119, 184;
429/96–100, 149, 163, 187

FIG. 5 is a right side view thereof;

See application file for complete search history.

FIG. 6 is a top plan view thereof; and

(56) **References Cited**

FIG. 7 is a bottom plan view thereof; and,

U.S. PATENT DOCUMENTS

FIG. 8 is a perspective view showing an example of the usage of the battery pack in which a plurality of the battery packs are coupled to each other.
